ELECTRICAL SWITCH

Saul I. Slater, Woodside, N. Y., assignor to Slater
Electric & Mfg. Co., Inc., Woodside, N. Y., a
corporation of New York

Application April 18, 1951, Serial No. 221,636

1 Claim. (Cl. 200—67)

1 The present invention relates to electrical switches and particularly to toggle switches of the type commonly utilized for installation in lighting circuits of buildings. As is usual in switches of this type the switch is composed of a handle member operating a commutator piece acting in one position as a bridge from one fixed terminal to the other and in another position being idle, the connection between the two terminals being then broken.

In such switches difficulty is encountered in that the terminals, which are resilient, tend to vibrate when the commutator piece snaps into position therebetween. Switches intended to be used in circuits in which the load is tungsten filament lamps must be designed with the positive temperature coefficient of the load in mind. As a result of this load characteristic, the current is very much higher at switch closing than at normal switch opening. In the case of the ordinary 115 volt tungsten type mazda lamps, the initial current is 10 times that of the stabilized current. Thus, in a switch of 10 ampere rating the design is such as to render the switch operable on currents of 100 amperes at closing. The switch, however, is designed to break a current of only 10 amperes. The 100 ampere flow lasts for only a fraction of a second varying from about a 500th of a second to about a 250th of a second. In prior switches vibration of the terminals upon a sudden impact of the commutator at the instant of "make" causes breaking of the current at the time when it is at its peak value and resultant burning and pitting of the surfaces of both the commutator and each of the two contact terminals. This, of course, results in rapid deterioration and ultimate inoperativeness of the switch. This vibration has therefore been a major and continuing problem especially in connection with fast acting switches of the toggle type.

It is therefore the primary object of my invention to provide an electrical switch of the toggle type in which the parts are so arranged as to prevent chattering and vibrating of the resilient terminal members thereby eliminating pitting and deterioration of the terminal members and of the commutator member thereby prolonging the life of the switch.

Other objects and features of the invention will be apparent when the following description is considered in connection with the annexed drawings, in which

Figure 1 is a vertical cross-sectional view of a switch made in accordance with my invention, the switch parts being in operated or circuit closing position;

2 Figure 2 is a vertical cross-sectional view of the switch of my invention, the section being taken on the plane of the line 2—2 of Figure 1;

5 Figure 3 is a view similar to Figure 1 but showing the switch in its inoperated or off position;

Fig. 4 is a cross-sectional view of the switch, the view being taken on the plane of the line 4—4 of Figure 3;

10 Figure 5 is a detail view showing one of the terminals of the switch; and

Figure 6 is a fragmentary rear view of the switch with the outer housing broken away showing particularly the mode of cooperation of a stop member with the resilient terminals.

15 Referring now to the drawing, the switch is composed of a body 10 made of insulating material and ordinarily of a suitable plastic which body is molded to form supports for the operating members of the switch as well as for the fixed terminals. An operating handle 11 likewise formed of plastic is pivotally mounted in the housing member 10 by means of pins 12 which lie in slots 13 in the housing 10. Integrally formed with the handle 11 is a lug 14 which extends 20 within a coil spring 15, the opposite end of which surrounds a projection 16 extending from a commutator member 17. The commutator member 17 is also pivotally mounted in the housing, the pivotal mounting being accomplished by having extensions 18 of the commutator member 17 extend into slots 19 molded in the body 10.

25 The parts are held in the position indicated by means of a plate 20 fixed to the face of the housing and having inwardly bent portions (not shown) which bear against the pins 12 of the handle 11.

30 Terminals of the shape shown in Figure 5 and designated respectively 21 and 22, are inserted in keyed slots in the housing member as is indicated particularly in Figures 3 and 4. The upwardly extending arms 23 and 24 of these terminal members are inclined inwardly and the entire terminal is formed of somewhat resilient material.

35 These arms or contact portions 23 and 24 of the terminals normally rest against a stop member 25 formed in the shape of a T and extending from the rear portion of the housing forwardly. Projecting inwardly from either side of the housing substantially in line with the bar of the T-shaped member 25 are two stops 26 and 27.

40 These stops cooperate with the T-shaped stop 25 to form small gaps 28 in which the contact arms 23 and 24 are positioned and within which the movement of these arms is limited.

45 On the side of the housing opposite the T-shaped member 25 there is an inwardly project-

3

ing rib 30 which serves to limit the movement of the commutator in one direction, the movement in the opposite direction being limited in the like manner by the bar of the T-shaped member 25.

As will be seen by referring particularly to Figure 2 the commutator member 17 is wider than the distance between the contact arms 23 and 24 when those arms lie against the outer edges of the bar of the T-shaped member 25. Therefore when the handle is thrown into the "on" position, the commutator member 17 strikes the contact arms 23 and 24, moves them outwardly against the resilient force exerted by these arms and brings them to rest against the stops 26 and 27. Due to the stops 26 and 27 and, to a lesser extent to the preloading of the resilient arms 23 and 24, when the commutator enters between the contact arms and forces them outwardly to the position shown in Figure 2 and against the stops 26 and 27, there can be no vibration of the contact arms against the commutator since the contact arms bear heavily against the commutator as it moves into position and are stopped in fixed positions against the stops 26 and 27. Thus they are always prevented from vibrating with respect to the commutator and therefore no arcing occurs and no resultant pitting of the contact arm surface or of the cooperating commutator surface.

Tests have shown that a switch in accordance with the instant construction, will carry an inrush of current on making contact of 100 amperes for the first 250th to 500th of a second where in ordinary switches this 100 ampere inrush creates extreme arcing because of the usual vibration and chattering of contacts during the "make" period. The present construction achieves this result because it eliminates the vibration-caused "breaking" of the contacts each time the switch is snapped on. This of course results in the materially lengthened useful life. The elimination of chattering in the manner above-described materially lengthens the life of the switch and, in fact, tests have indicated that the switch life is well over double that of a similar switch which is not provided with the stop members above-described.

Even in those cases where, due to the mechanical tolerances allowed, the stops do not fit tightly against the terminals and a tolerance of several thousandths of an inch spacing may be present between the stop and the terminal when the commutator is in circuit closing position, oscillation

4

and vibration of the terminals is substantially stopped due to the fact that the stop interferes with and damps the free vibration of the resilient member. This action may be likened to the effect of placing a solid object close to a vibrating string such as a violin string. The string ceases to vibrate even though the object does not touch the string when at rest but merely acts to damp the vibrations thereof.

While I have described a preferred embodiment of the device of my invention, it will be understood that many alterations and modifications might be made without departing from the spirit of my invention. I wish therefore to be limited not by the foregoing description but, on the contrary, solely by the claim granted to me.

What is claimed is:

In an electrical switch of the toggle-operated type having a pair of fixed terminals, and a commutator for entering therebetween to close the circuit, and in which the switch parts are within an insulating housing, in combination, a T-shaped stop member projecting from said housing and extending between the terminals, the terminals being formed of resilient material and normally resting against said stop member, additional stop members projecting from the housing and spaced from said first-mentioned stop member, one of said second-mentioned stop members being on the opposite side of each of said terminals from said first-mentioned stop member thereby forming limit stops for movement of said terminals in each direction, the commutator being adapted to enter between said terminals when in circuit-closing position thereby forcing said terminals outwardly against said second-mentioned limit stops, thereby preventing chattering of said resilient terminals as the commutator moves into circuit-closing position.
